ELECTRIC VALVE CIRCUIT

Emil J. Remscheid, Scotia, N. Y., assignor to General Electric Company, a corporation of New York

Application December 21, 1938, Serial No. 247,060

7 Claims. (Cl. 175—363)

My invention relates to electric valve circuits and more particularly to deionization circuits for electric valve apparatus employing ionizable media.

- 5 Where electric valve means employing ionizable media are used in electric translating apparatus, it is frequently desirable to provide deionization circuits for collecting the positive ions at the end of the normal intervals of conduction.
- 10 Heretofore, the prior art arrangements for effecting deionization of electric valves have been relatively complicated in nature and construction and required considerable inspection and maintenance. In accordance with the teachings
- 15 of my invention described hereinafter, I provide a new and improved deionization circuit for electric valve apparatus which is simple in construction and operation and which offers additional advantages in electric valve performance.
- 20 It is an object of my invention to provide a new and improved electric valve circuit.

It is another object of my invention to provide a new and improved deionization circuit for electric valve apparatus employing an ionizable medium.

25 It is a further object of my invention to provide a new and improved deionization circuit for electric valve apparatus of the type employing a mercury pool cathode and an associated immersion-ignitor control member.

30 In accordance with an illustrated embodiment of my invention, I provide a new and improved control circuit for electric valve apparatus. Electric valve means of the type employing an ionizable medium is connected between an alternating current supply circuit and a direct current load circuit. The electric valve means is of the type employing mercury vapor as an ionizable medium and the electric valve means comprises an anode, 35 a mercury pool cathode and an immersion-ignitor control member associated with the cathode. An auxiliary electrode or baffle is placed in the vicinity of the anode and is permanently connected to the anode through an energy consuming means such as a resistance. The resistance and the auxiliary electrode constitute a deionization circuit for the electric valve means. In one embodiment of my invention, a control or excitation circuit is connected between the immersion-ignitor control member and the common juncture of the resistance and the auxiliary electrode and energizes the control member to render the electric valve means conductive by the conduction of unidirectional current to the control member. The control circuit comprises an

electronic discharge device which may be of the controlled type to render the principal or power electric valve means conductive at a predetermined time during the cycle of applied anode-cathode voltage. In another embodiment of my invention, the excitation circuit is connected directly to the anode of the electric valve means.

For a better understanding of my invention, reference may be had to the following description taken in connection with the accompanying drawing and its scope will be pointed out in the appended claims. Figs. 1 and 2 of the drawing diagrammatically illustrate embodiments of my invention as applied to electric valve translating apparatus for transmitting power between an alternating current circuit and a direct current circuit.

In Fig. 1 of the accompanying drawing, I have diagrammatically illustrated my invention as applied to an electric valve translating circuit for transmitting power between an alternating current circuit 1 and a direct current circuit 2 through a transformer 3 having a plurality of primary windings 4 and a plurality of groups of secondary windings 5 and 6. An interphase 5 transformer 7 connects the groups of secondary windings 5 and 6 to one terminal of the direct current circuit 2. The translating apparatus also comprises a plurality of electric valve means 8-13, inclusive, which are of the type employing an ionizable medium such as a gas or a vapor. For the purposes of illustration, the electric valve means 8-13 are shown as being of the type employing a self-reconstructing cathode 14 such as a mercury pool, an anode 15, and a control member 16 which may be of the immersion-ignitor type having an extremity immersed in the mercury of the cathode 14. The immersion-ignitor control member 16 of each of the electric valves is preferably constructed of a material having an electrical resistivity which is relatively great with respect to that of the associated mercury pool cathode. The immersion-ignitor control member 16 may be constructed of a poorly conducting or semi-conducting material such as boron-carbide or silicon-carbide. Each of the electric valve means 8-13 is provided with an auxiliary electrode or baffle 17 which is placed in the vicinity of the associated anode 15 and which may substantially surround the anode 15. The auxiliary electrode 17 may be constructed of graphite and may be perforated; and the number and the size of the perforations are designed to control the effect of the auxiliary electrode on the associated anode 15. I provide a plurality

of deionization circuits 18-23 associated with the electric valve means 8-13, respectively. Each of the deionization circuits is responsive to the anode voltage or to the polarity of the anode voltage of the associated electric valve means and is permanently connected to the anode and comprises a suitable energy absorbing means, such as a resistance 24, which serves to absorb the energy incident to the deionization of the mercury vapor of the associated electric valve means after the normal interval of conduction for that electric valve means. I have found that the deionization circuits operate very satisfactorily when the value of the resistance 24 is 500 ohms; this value of resistance has proved to be a critical value for the particular electric valves in which the invention has been embodied.

I also provide a plurality of control or excitation circuits 25 each associated with a different one of the electric valve means 8-13. For the purpose of illustration, only excitation circuit 25 associated with electric valve means 8 is shown. Each of the control circuits 25 is connected between the immersion-ignitor control member 16 of the associated electric valve means and a common juncture 26 of the associated auxiliary electrode 17 and the resistance 24. The control circuit 25 effects energization of the immersion-ignitor control member 16 to render the electric valve means conductive in a predetermined order and at predetermined times during the cycle of applied anode-cathode voltage. Each of the control circuits 25 may comprise a suitable electronic discharge device 27 which is preferably of the type employing an ionizable medium, such as a gas or a vapor, and which may comprise a control member or grid 28 which renders the electronic discharge device 27 conductive to effect energization of the immersion-ignitor control member 16 at a predetermined time during the cycle of applied anode-cathode voltage of the associated electric valve means. A current controlling or limiting resistance 29 may be connected in series relation with the electronic discharge device 27 in each of the control circuits 25 in order to control the magnitude of the current transmitted to the associated immersion-ignitor control member 16. The input circuits of the electronic discharge devices 27 of the control circuits 25 may be energized from a suitable source of periodic voltage correlated in phase and frequency with respect to the voltage of the alternating current circuit 1, or with respect to the applied anode-cathode voltages of electric valve means 8-13. The input circuits may be energized from the alternating current circuit 1 through a circuit comprising a transformer 30 having a plurality of primary windings 31 and a plurality of secondary windings 32. Each of the secondary windings 32 is connected to a different one of the control grids 28 of the electronic discharge devices 27 of control circuits 25. A suitable source of negative unidirectional biasing potential, such as a battery 33, may be connected in circuit with the control grids 28. A phase shifting device, such as a rotary phase shifter 34, may be interposed between the transformer 30 and the alternating current circuit 1 to control or adjust the phase of the periodic voltages impressed on grids 28 of electronic discharge devices 27 and hence to control the times during the cycles of applied anode-cathode voltage at which the electric valve means 8-13 are rendered conductive.

75 The operation of the embodiment of my in-

vention shown in Fig. 1 of the accompanying drawing will be explained by considering the system when it is operating as a rectifier to energize the direct current circuit 2 from the alternating current circuit 1. It will be understood that the electric valve means 8-13 conduct current in a predetermined order or sequence and that each electric valve means conducts current for substantially 120 electrical degrees. The times during which the electric valve means 8-13 are rendered conductive during the respective cycles of applied anode-cathode voltage determine the magnitude of the voltage applied to the direct current circuit 2. The electric valves 8-13 are rendered conductive by transmitting to the immersion-ignitor control member 16 a current of predetermined magnitude in order to initiate a cathode spot on the surface of the associated mercury pool cathode 14 and thereby effect ionization of the mercury vapor between the anode 15 and the cathode 14. The control circuits 25 are rendered conductive by the proper sequential operation of the control circuits associated with grids 28 to transmit unidirectional currents to the immersion-ignitor control members 16. 25

By virtue of the improved deionization circuit which I provide, I have found that the normal load rating or current rating of electric valve means of this type may be substantially increased. For example, I have found that by employing my 30 deionization circuit, the normal load rating of the electric valve means is doubled and that the instantaneous or temporary overload rating is tripled. When the electric valve means 8-13 are conductive, current is transmitted between 35 the anode and the cathode by the ionization of the mercury vapor. Part of the current transmitted is conducted by means of electrons and part is conducted by positive mercury ions. The electrons during the normal period of conduction 40 flow toward the anode and the positive ions flow toward the cathode. As will be well understood by those skilled in the art, current is 45 commutated among the various electric valve means 8-13 by the sequential change in the voltages impressed on the various anodes; that is, current is conducted by that electric valve means of each group associated with windings 5 and 6, the anode of which is more positive than the anode of any other associated electric valve 50 means. At the time current is commutated from an electric valve means and immediately thereafter, the mercury vapor of that electric valve means is highly ionized and the energy due to such ionization must be dissipated in order that 55 the electric valve means be restored to a non-conductive condition. Immediately after commutation, due to the cyclic variation of the applied anode-cathode voltage, the anode of a particular electric valve means becomes negative in 60 potential with respect to the associated cathode. Under these conditions, the electrons move toward the cathode and the positive ions move toward the anode. The energy, due to the deionization of the medium, is therefore dissipated 65 in the form of heat on the cathode and the anode. Due to the relatively large number of mercury vapor positive ions, the amount of heat generated by the impinging positive ions on the anode is relatively large, causing an appreciable 70 increase in temperature of the anode and an appreciable rise in temperature of the entire electric valve means. It will be understood that if the rise in temperature for a particular electric valve means becomes sufficiently great, the anode may 75

tend to operate as a cathode due to the formation of a cathode spot on the anode caused by the impinging positive ions.

The deionization circuits 18-23 offer several distinct advantages. These circuits increase the current rating of the electric valve means and also tend to prevent arc-backs. During the working or positive half cycles, the auxiliary electrode 17 assumes a potential intermediate that of the anode and the cathode by virtue of the high-resistance electrical connection to the anode through the resistance 24. During the first part of the inverse half cycle, that is, after the commutation of current from a particular electric valve, the auxiliary electrode 17 remains at substantially the same potential with respect to the cathode. The duty imposed on the anode is substantially reduced during the deionization period, since the space which must be deionized by the anode is now limited to the space between the anode and the auxiliary electrodes and the positive ion current is accordingly reduced below that which would be obtained were the auxiliary electrodes not present. Since the rating of electric valve means of this type is in a measure dependent upon the maximum temperature of the electric valve means during the cycle of operation, it is to be understood that the presence of the auxiliary electrode 17 and the associated deionization circuit increases the current rating of the electric valve means.

The deionization circuits also tend to prevent arc-backs by limiting the maximum temperature of the associated anode. Without attempting a rigorous explanation of the mechanism by virtue of which this advantage is obtained, this improved operation may be explained in the following manner. One of the most likely theories is that immediately after commutation of current from a conducting valve of this type, the mercury vapor positive ions tend to move toward the anode. The velocity of these ions is determined by the difference in voltage between the anode and the cathode and the velocity, of course, increases as the ions approach the anode. If the ions attain a reasonably great velocity and if the number of ions is large, there is produced on the surface of the anode a cathode spot due to the heat generated by the impinging positive ions. Under such conditions, the anode would tend to operate as a cathode. However, by the use of the auxiliary electrode 17 connected in accordance with the teachings of my invention, that is, by connecting the auxiliary electrode to the anode through a relatively high resistance, there is provided a path for the dissipation of the energy due to the positive ions which migrate toward the anode during the deionization period. The auxiliary electrode collects the positive ions moving toward the anode; and by virtue of the collection of the positive ions, current flows through the resistance 24, and the energy is dissipated in the resistance. Of course, the presence of the auxiliary electrode 17 tends to reduce the voltage gradient within the space between the anode and the auxiliary electrode, thereby reducing the velocity of the positive ions which do ultimately migrate to the anode. In addition, the quantity or number of the positive ions which finally reach the anode is substantially reduced because the auxiliary electrode is interposed between the cathode and the anode. The temperature of the auxiliary electrode is maintained below that value which would cause the auxiliary electrode to operate as a cathode, because the resistance 24

limits the magnitude of the current which can flow due to the deionization of the mercury vapor. In this manner, the resistance 24 prohibits the generation of an excessive amount of heat on the auxiliary electrode 17 by limiting the amount of current which can be conducted from the ionized mercury vapor through the auxiliary electrode to the power circuit during the deionization interval.

It will be appreciated that by virtue of my invention there is provided an improved arrangement for effecting deionization of an electric valve means of the type employing an ionizable medium, without sacrificing the efficiency of the system.

Fig. 2 diagrammatically illustrates another embodiment of my invention and is a modification of the arrangement shown in Fig. 1; corresponding elements have been assigned like reference numerals. In the arrangement of Fig. 2, the electronic discharge device 27 is connected directly to the anode 15 of the associated electric valve means 8, and the cathode of the electronic discharge device 27 is connected to the control member 16 of the electric valve means 8. The input circuit of the electronic discharge device 27 is connected between the control grid 28 and the common juncture of the cathodes of the electric valve means 8-13; that is, the one terminal of the input circuit is connected to the positive terminal of the direct current circuit 2. The arrangement of Fig. 2 operates in substantially the same manner as that explained above in connection with Fig. 1. At predetermined times, depending upon the phase of the voltage impressed on the control grid 28, electronic discharge device 27 is rendered conductive, effecting energization of the immersion-ignitor control member 16 of the associated power electric valve means. Energization of the control member 16 establishes an arc discharge between the cathode and the anode, rendering the principal electric valve means conductive. The deionization circuit including the resistance 24 absorbs the energy due to the deionization of the mercury vapor, effecting an increase in the current rating of the electric valve means and tending to prevent arc-backs.

While I have shown and described my invention as applied to a particular system of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, an alternating current circuit, a load circuit, electric translating apparatus connected between said circuits and comprising electric valve means employing an ionizable medium and having an anode, a cathode, a control member of the immersion-ignitor type and an auxiliary electrode in the vicinity of said anode, a control circuit responsive to the voltage of said anode and comprising an electronic discharge device for effecting energization of said control member to render said electric valve means conductive, and a deionization circuit connected to said auxiliary electrode and being responsive to the voltage of said anode.

2. In combination, an alternating current circuit, a load circuit, electric translating apparatus connected between said circuits and comprising

- electric valve means employing an ionizable medium and having an anode, a cathode, a control member of the immersion-ignitor type and an auxiliary electrode in the vicinity of said anode, 5 a control circuit connected between said anode and said control member and comprising a unidirectional conducting device responsive to the voltage of said anode for effecting energization of said control member to render said electric 10 valve means conductive, and a deionization circuit connected between said control circuit and said auxiliary electrode.
3. In combination, an alternating current circuit, a load circuit, electric translating apparatus 15 connected between said circuits and comprising electric valve means employing an ionizable medium and having an anode, a cathode, a control member of the immersion-ignitor type and an auxiliary electrode in the vicinity of said anode, 20 a control circuit responsive to the polarity of the voltage of said anode and comprising a unidirectional conducting device for transmitting unidirectional current to said control member to render said electric valve means conductive, 25 and a deionization circuit connected to said auxiliary electrode and being responsive to the voltage of said anode and comprising an energy consuming means for dissipating energy incident to the deionization of said medium.
- 30 4. In combination, an alternating current circuit, a load circuit, electric translating apparatus connected between said circuits and comprising electric valve means employing an ionizable medium and having an anode, a cathode, a control 35 member and an auxiliary electrode in the vicinity of said anode, a resistance connected between said anode and said auxiliary electrode, and a control circuit for energizing said control member and being connected between said control member and the common juncture of said resistance and said auxiliary electrode.
- 35 5. In combination, an alternating current circuit, a load circuit, electric translating apparatus connected between said circuits and comprising electric valve means employing an ionizable medium and having an anode, a cathode, a control member of the immersion-ignitor type and an auxiliary electrode in the vicinity of said anode, a control circuit comprising an electronic discharge device responsive to the polarity of the voltage of said anode for effecting energization of said control electrode to render said electric valve means conductive by initiating an arc discharge between said cathode and said anode, and a resistance connected between said anode and said auxiliary electrode for dissipating the energy incident to the deionization of said medium when said anode becomes negative in potential with respect to said cathode after the normal interval of conduction of said electric valve means. 5
6. In combination, an alternating current circuit, a load circuit, electric translating apparatus 10 connected between said circuits and comprising electric valve means employing an ionizable medium and having an anode, a cathode, a control member and an auxiliary electrode in the vicinity of said anode, a deionization circuit comprising 15 a resistance connected between said anode and said auxiliary electrode, and a control circuit connected between the common juncture of said resistance and said auxiliary electrode and said control member and comprising an electronic discharge device for transmitting unidirectional current to said control member to render said electric valve means conductive. 20
7. In combination, an alternating current circuit, a load circuit, electric translating apparatus 25 connected between said circuits and comprising electric valve means employing an ionizable medium and having an anode, a cathode, a control member and an auxiliary electrode in the vicinity of said anode, a deionization circuit comprising 30 a resistance connected between said anode and said auxiliary electrode, a control circuit connected between the common juncture of said resistance and said auxiliary electrode and said control member and comprising an electronic discharge device for transmitting unidirectional current to said control member to render said electric valve means conductive and means for controlling the conductivity of said electronic discharge device. 35
